G. F. PAUL

WATER HEATER

Filed Aug. 25, 1921

30 30 Inventor
George F. Paul

By Benjamin, Rhoads & Lindsay.
Atts.

UNITED STATES PATENT OFFICE.

GEORGE F. PAUL, OF LOS ANGELES, CALIFORNIA.

WATER HEATER.

Application filed August 25, 1921. Serial No. 495,271.

To all whom it may concern:

Be it known that I, GEORGE F. PAUL, a citizen of the United States, residing at Los Angeles, in the county of Los Angeles and State of California, have invented a new and useful Improvement in a Water Heater, of which the following is a specification.

My invention relates to water heaters, and more especially to what is generally known as an auxiliary water heater for use in connection with a boiler.

My improved device is so constructed that it may be readily secured in an opening made in the front plate or wall of the boiler preferably below the water-line so that the walls of the circulating passages of my device will be submerged in the hot water in the boiler so as to heat the water in my device to a temperature desirable for domestic and other uses.

The apparatus is so constructed that it is practically a unit that requires but a small amount of labor to install, and therefore is capable of being set up by inexperienced persons, or by skilled mechanics in a comparatively short time. Also, my water heater requires no special tools in installing the same, and its structure is such that several units may be readily connected together by piping or nipples when a greater quantity of hot water is desired. A further object of my invention is to provide a structure which is both economical in construction and of added efficiency in operation in that the partition hereinafter mentioned may be much more cheaply manufactured than round pipe and may also be provided of less thickness thereby facilitating the heating of the water during its passage through the device.

I prefer to carry out my invention in substantially the manner hereinafter more fully described, and as particularly pointed out in the claims. Reference will now be made to the accompanying drawings that form a part hereof, in which—

Figure 1 is a central longitudinal section of my heater showing it installed upon a fragmental portion of a boiler.

Figure 2 is a side elevation of the structure illustrated in Figure 1, a portion of the tube being broken away.

Figure 3 is a vertical section taken on line 3—3, Figure 2, looking in the direction of the arrows.

Figure 4 is a transverse vertical section 55 of the tube or passageway the view being taken on line 4—4, Figure 2.

Figure 5 is a view taken on line 5—5, Figure 1, and looking in the direction of the arrows.

Figure 6 is a vertical front elevation of the outside or main shell of the device,

Figure 7 is a front view showing the manner of mounting a plurality or battery of units for increasing the quantity of 65 water heated.

In the drawings similar reference characters are employed to designate the same parts in the several views, and by referring, first, to Figure 1, it will be seen I may make 70 use of the hand cleanout, or I form an opening 10 in the front plate 11 of the boiler in a horizontal plane preferably below the water level and above the crown sheet or the tubes 12 thereof, and through this opening 10 is passed the tube of my improved heater, as will be hereinafter more fully explained.

The main portion of my device consists of a hollow casting that comprises a cylindrical hollow casing 13 the end of which is flanged, as at 14, to provide a flat plate for mounting upon plate 11 around the opening and secured in position by bolts, rivets or the like. The flanged end of casing 13 is 80 internally threaded to receive the threaded outer end of a tube 15 that is closed at its opposite end, as seen in Fig. 1, and prior to securing the structure I prefer to place a suitable packing or gasket 16 that compresses into the space between tube 15 and plate 11 when the structure is tightened into position.

The casing 13 extends out from the boiler plate 11, as seen in Fig. 2, and its upper segment is provided with an upright discharge stub 17 that is internally threaded to receive the lower end of the hot-water discharge pipe 18, the axis of which is transverse or at a right angle to the axis of casing 13. Depending from the under segment of casing 13 is a cylindrical embossment 19, the axis of which is horizontally disposed and intersects the axis of casing 13, as seen in Figures 1 and 2. The interior of this embossment communicates with the interior of the casing through a neck or restricted passageway 20 (Fig. 3), and its opposite

ends are interiorly threaded to receive, respectively, a closure plug 21 and the supply pipe 22.

In order to keep the currents of water separated or continuous in both directions in tube 15 and casing 13, I have employed a partition 23 of V-shape in cross-section that is inverted when placed in the tube and which extends to near the inner end of tube 15, as seen in Fig. 1 of the drawings. The forward end of the partition 23 extends into the casing where it straddles neck 20 and it terminates in substantially the transverse plane of an annular shoulder 24 in the casing. The manner of securing the partition is to provide lateral flanges 25 upon its outer end to which is suitably secured a metal or other disk 28 that is wider than the bore of casing 13 so that one of its surfaces bears against the outer face of shoulder 24 thereby closing the end of the partition as well and the outer portion of the casing and prevents the intermixing of the cool and hot streams or currents of water. In order to secure the structure just described in rigid relation to the casing, I internally thread the outer end of said casing back to shoulder 24 and screw therein a suitable plug 29 until it bears against disk 28 thereby retaining the same in position. By removing plug 29 the disk may be grasped and thereby draw out partition 23, all of which will be understood by reference to Fig. 1 of the drawings.

For ordinary domestic purposes only a single unit is necessary, but when greater quantities of hot water are desired I may make a plurality of holes in the boiler alining horizontally and connect two or more casings or units by nipples 30, as seen in Fig. 7 of the drawings, the ends of the nipples being secured into the opposite ends of embossment 19 thereby forming a "battery", it being understood each casing is provided with its respective tube 15 that extends into the boiler and is submerged in the water therein.

In operation, the water to be heated enters through supply pipe 22, passing from embossment 19 through neck 20 and into pipe 15 between the walls of partition 23.

The head under which the water is supplied causes its circulation inwardly through the V-shaped channel 23 and backwardly around the exterior of the sides of the partition to discharge pipe 18, and during its circulation inwardly through the partition and outwardly between the walls of the partition and tube 15 it is heated by induction from the surrounding heated water or steam contained in the boiler.

In order to position the V-shaped partition 23 in assembling the structure, I prefer to form a notch or recess 31 in the upper segment of annular shoulder 24 into which the

apex of the partition will fit when the latter is inserted into tube 15; this notch also preventing any relative rotative movement of disk 28 when the plug nut 29 is being screwed into tight position.

While I have herein illustrated and described the preferred manner of carrying out my invention, it of course will be obvious that immaterial modifications may be made to the construction and arrangement of the parts without departing from the principle I have disclosed, and I, therefore, desire it understood that such changes are fully contemplated as coming within the scope of the appended claims.

What I claim is:—

1. A unit for a water heater, in combination with a boiler, said unit comprising a cylindrical casing, a discharge stub in the upper portion of said casing, a hollow feed embossment at right angles to the discharge stub extending across the lower segment of the casing and having ports at both ends, a tube extending axially from one end of said casing into the boiler, a wall extending longitudinally of said tube and casing whereby the same is divided into cool water and hot water passageways, a feed pipe connected with said feed embossment, and a discharge pipe connected with said discharge stub.

2. A water heater comprising in combination with a boiler, a plurality of elements each consisting of a horizontally disposed cylindrical casing, a discharge stub extended upwardly therefrom at a right angle thereto, a horizontally disposed hollow feed embossment upon the lower portion of said casing and communicating with the interior thereof; said embossment being disposed tangentially of said casing and having ports at both ends, adjacent ports of said elements communicating with each other, a tube secured at its outer end in said casing and extended axially therefrom into said boiler; said tube closed at its inner end, and a wall extending longitudinally of said tube and casing whereby the same is divided into cool water and hot water passageways.

3. A water heater comprising a cylindrical casing having a discharge stub in its upper segment, a hollow feed embossment opening at opposite ends extending tangentially across its lower segment and opening into said casing, a tube secured to and extended axially from one end of said casing, a dividing element in said casing and tube whereby the same are divided into ingoing and outgoing passageways that communicate at the inner end of said tube opposite said casing, a closure for the outer end of said dividing element within the casing, and means for rigidly mounting said closure within said casing.

4. A water heater comprising a cylin-

drical casing having a discharge stub in its upper segment, a hollow feed embossment opening at opposite ends extending across its lower segment and opening into said casing, a tube secured to and extended axially from one end of said casing, a partition of inverted V-section disposed in said casing and tube and terminating adjacent the end of said tube opposite the casing, a disk secured to the end of said partition within said casing, a shoulder in said casing engaged by said disk, and a plug screwed into the adjacent end of said casing to press said disk against said shoulder whereby the partition is securely positioned in the casing and tube and straddles the inlet opening of the former.

5. A water heater comprising a cylindrical casing having a discharge stub in its upper segment, a hollow feed embossment extending across its lower segment and opening into said casing, a tube secured to and extended axially from one end of said

casing, a removable partition consisting of a metal sheet bent to an inverted V-section 25 that is disposed in said casing and tube and terminating adjacent the end of said tube opposite the casing, a shoulder in said casing engaged by said disk; said shoulder provided with a recess in its upper segment 30 in which the apex of said V-section partition is seated and prevented from relative movement by the disk-securing means, and a plug screwed into the adjacent end of said casing to press said disk against said shoulder whereby the partition is securely 35 positioned in the casing and tube and straddles the inlet opening of the former.

Signed at Los Angeles, county of Los Angeles and State of California, this 8th 40 day of August, 1921.

GEORGE F. PAUL.
